UNITED STATES PATENT OFFICE.

CHESTER C. SMALL, OF NEWTON, MASSACHUSETTS, ASSIGNOR TO UNITED SHOE MACHINERY COMPANY, OF PATERSON, NEW JERSEY, A CORPORATION OF NEW JERSEY.

NAIL-ASSORTING MECHANISM.

1,028,972.

Specification of Letters Patent. Patented June 11, 1912.

Original application filed August 1, 1902, Serial No. 117,935. Divided and this application filed February 11, 1904. Serial No. 193,131.

To all whom it may concern:

Be it known that I, CHESTER C. SMALL, a citizen of the United States, residing at Newton, in the county of Middlesex and State of Massachusetts, have invented an Improvement in Nail-Assorting Mechanism, of which the following description, in connection with the accompanying drawings, is a specification, like letters on the drawings representing like parts.

This invention has for its object the production of a novel apparatus by which to assort axially tapered headless nails and arrange them with their corresponding sides in predetermined relative positions.

The heads of the tapered headless nails such as have been heretofore assorted heads and points in the same direction for nailing together heel-lifts, have been substantially square at the head end, and such nails have been used chiefly in what is called "blind-nailing," wherein the nails attach a heel to the sole, and a top-lift is thereafter spanked on the larger ends of the nails not fully driven into the heel, and they have sometimes been used for surface nailing in connection with cheap work.

The apparatus to be herein described and claimed has been devised and is particularly intended for use in assorting "English slug-nails", or nails whose heads are oblong instead of square as heretofore, although this apparatus may also be employed for axially assorting ordinary heel nails which are square in cross section. English slug-nails are used mostly in surface nailing, in which they serve not only to attach a heel to a shoe, but they also serve the purpose of slug-nails to resist wear and also ornament the tread of the heel.

To insure an ornamental appearance of the heel it is essential that the oblong heads be arranged uniformly around the heel. To this end, in assorting and delivering these English slug-nails, it becomes necessary not only to assort the nails as to heads and points, but they must also be turned axially that their wide parallel sides may be relatively arranged to enter under like conditions the nail-block, such axial turning of

the nails enabling all the nails to be driven into the heel or other stock with their parallel sides contiguous. To do this I have in the embodiment of the invention herein shown provided means operative after the 55 nails leave the usual assorting mechanism for turning the nails axially or about their longitudinal axes, so that the nails when delivered will be similarly arranged as to their parallel sides. The nails must also be 60 directed in their passage from the axial assorting mechanism to the nail-block in such way that they will be restrained from free axial rotation, and to accomplish this I have connected with said axial assorting mechanism nail-guiding tubes having nail passage of a thickness less than the width of the nail.

I believe that I am the first to provide a nail-assorting mechanism adapted to receive nails arranged indiscriminately as to their axial positions and provided with means for arranging said nails axially whereby all the nails are presented in predetermined position as to the arrangement 75 of their sides.

In the following description and claims reference is to be made to the "width" and the "thickness" of the nails which are designed to be handled in this machine. By 80 the term "width" I mean the greater dimension of the nail measured at right angles to its length, and by the term "thickness" I mean the lesser dimension of the nail measured at right angles to its length. By the 85 term "side" as applied to the nails I mean that face which extends in the directions of the width and the length of the nail, and by the term "edge" as applied to the nail I mean that narrower face which extends in 90 the directions of the thickness and the length of the nail. That these nails may be driven properly into a heel I prefer to employ for pricking the nail-holes in the heel an awl such as described in my application Se. No. 95 117,935, filed August 1, 1902, from which this application is a division, said awl having a shape in cross section corresponding approximately with the shape of the nail.

Figure 1 in side elevation shows my in- 100

vention applied in one of the best forms now known to me to a well known form of machine for automatically assorting nails as to heads and points and loading them into compressed-heels; Fig. 2 in section on a larger scale shows a nail-controller forming part of said mechanism for assorting nails as to heads and points together with means embodying my invention for turning the 10 nails axially to a predetermined relative position so that the nails may enter properly the pockets and tubes for guiding them to the nail-block; Fig. 3 a cross sectional detail in the dotted line 3, Fig. 2, the figure 15 showing the shape of the chambers m' of said nail controller; Fig. 4 is a view looking at Fig. 2 from the left, some of the parts shown in said figure being removed; Fig. 5 shows the nail-controller of Fig. 2 in a different position; Fig. 6 is a view of the part 20 below the plane $x-x$, Fig. 4, the screw being in section; Fig. 7 is a cross section of a nail-guiding tube; Fig. 8 shows a top view of the templet and awl holes therein.

25 The framework A contains a power shaft A^{2x} having a pinion A^2 engaging a toothed gear A^3 fast on and rotating the main shaft A^4 , said shaft corresponding with the shaft indicated by like number in my said application and actuating the awl carrier not necessary to be herein described. The upper end of the framework A supports a frame A'^x that sustains a horizontally reciprocating nail-assorting apparatus comprising a hopper b having leading from it raceways c , c' , at the lower end of which is a lifter f^x having grooves that receive the endmost nails in the series of raceway grooves. The lifter is elevated at desired times by a cam f^2 to 40 enable the nails thereon to slide into grooves of a delivery portion h , the nails sliding therefrom by gravity.

The nails having their heads leading enter the chambers m' , see Figs. 2 and 3, of a nail-controller m , but the nails with their points leading meet the walls n^x of said chambers, as shown by dotted lines in Fig. 2, and are arrested thereby but do not leave the delivery portion h . When the controller is 50 turned in the direction of the arrow, Figs. 2 and 5, the arrested point-first nails move with it and are carried over into the lower raceway grooves b^x , and the head-first nails which entered chambers of the controller are 55 discharged therefrom into the grooves b^x point-first, as shown in Fig. 5. The shaft of the controller m is provided with a pinion m^2 that is actuated by a lever m^3 deriving its movement from a cam on a shaft sustained 60 in a frame A'^x and actuated at intervals when it is desired to discharge a series of nails. The raceway is reciprocated by eccentrics on the rotating shaft e^5 .

The parts so far referred to by letter are 65 substantially the same as represented in my

aforesaid application and in United States Patent No. 577,213, granted to me February 16, 1897. Instead, however, of the particular nail-assorting mechanism referred to, which is adapted to turn a series of nails leaving the grooves of the raceway or the delivery portion h , heads and points indiscriminately, so that all the nails may be delivered point-first, I may employ any other known or usual means for assorting the nails 75 as to heads and points.

I will now particularly describe apparatus constituting one embodiment of the invention to be herein claimed. The nails entering the nail-controller in the Patent No. 577,213, were substantially square in cross section, and were discharged immediately from the controller into pockets, and thence directly into suitable tubes or conductors. In a machine for handling English slug-nails it is necessary also before the nails are delivered to assort them axially—that is, to arrange them as to their sides—so that they may be delivered under the same conditions in order that they may be loaded or driven into heel blanks with their corresponding sides in predetermined relative positions. To effect this second assorting which I designate as axial assorting, I have in the present construction provided a secondary raceway a^x having a series of V-shaped grooves b^x , and the bottoms of the grooves at the delivery end of the raceway are cut in line with each groove to form a series of vertical pockets c'^x . Said raceway a^x is reciprocated with the raceways c and c' to facilitate movement of the nails therein.

The grooves b^x are so shaped that as the nails enter the grooves and contact with the sides thereof they will be axially positioned and will thereafter travel longitudinally in said grooves in the direction of the arrow in Fig. 2, one of the sides of each nail contacting with one wall of a groove and one of the edges being sustained by the other wall of the groove. It will be understood that the raceway is suitably actuated to cause the nails to travel longitudinally therein, and as the lower edge of the nail, positioned as described in the raceway, arrives above the narrow opening or pocket c'^x the nail will enter the opening and in so doing will be caused to assume a position with its sides in substantially vertical planes, thus finally turning the nail into the position predetermined by the shape of the opening or pocket of the nail guiding tubes, which tubes are continuations of said openings or pockets, as is shown most clearly in Fig. 2. It will be understood that the nails pass upon the raceway a^x from the controller m arranged indiscriminately as to their sides. In passing down the raceway, however, the nails gradually assume positions in which one side of each nail lies in 130

contact with one wall of the groove as above described. The length of the raceway α^x is such that before a nail reaches the opening c^x it has been brought into proper position to enter said opening, so that presentation of a nail in an improper manner to said opening is prevented. The nails are caused to advance along the raceway α^x by the reciprocating movement imparted to said raceway.

As herein shown the mechanism for axially assorting the nails is arranged for positioning the nails of the different raceways side by side, and to this end each nail enters each pocket in the same way, the sides of each nail lying next the walls d^x , see Fig. 4, of each of said pockets. The sides of the pockets at the lower end of the secondary raceway α^x are closed by a plate e^x held in place by screws 12. The underside of the downward extension of the secondary raceway α^x has a supporting plate h^x connected therewith by screws g . The plate has a series of slots i^x , and a portion of the edges 25 of each slot is cut away as at k^x to receive suitable shoulders l^x at the top ends of the upper members 13 of the nail-guiding tubes employed to lead the nails to the foot g^2 .

The upper members 13 of the nail-guiding tubes are flattened or shaped to present a throat in continuation of the openings or pockets c^x narrower in width than the width of the nail whereby the nails entering therein, as shown in Fig. 7, are prevented from turning, are all accurately guided, and arrive at the foot g^2 with their sides facing in the line of driving. The portion 13^x of each nail-guiding tube is flexible that it may be positioned in the 40 nail-foot in accordance with the desired arrangement of nail-holes in said foot, and said tubes are also capable of being twisted so as to deliver the nails with the wide sides of the adjacent nails contiguous as shown 45 in Fig. 8 or extending transversely of the line in which the series of nails is driven, or in any other desired axial relation to one another.

Having described my invention, what I 50 claim and desire to secure by Letters Patent is:—

1. In a machine of the class described, a raceway for the passage of nails, said raceway being provided with grooves shaped 55 and arranged to cause the nails to arrange themselves with their corresponding sides in predetermined relative positions, and means for receiving nails from said raceway constructed to control the axial position of 60 the nails.

2. In a machine of the class described, a raceway presenting a groove provided in its bottom near its delivery end with a nail-receiving opening of a width less than the 65 width of the nail, said opening being shaped

to insure the delivery of a nail from the groove with one of its edges upturned and arranged to cause nails to be successively delivered from said groove and to turn about their axes in passing therefrom into said 70 opening.

3. A raceway having a groove to sustain by one of its side walls one of the two sides of a nail, the opposite side wall of the groove directing one of the two edges of the nail, 75 said groove having an opening narrower than the width of the nail to be received and extending through its floor near its lower end which opening is entered by the edge of the nail, whereby nails as they pass into said 80 opening have their two sides positioned always in the same manner.

4. In a machine of the class described, nail-guiding tubes, said tubes having passageways extending throughout their length, 85 which are narrower than the width of the nails to be guided therein, whereby said nails are restrained from free axial rotation, said tubes being flexible and adapted to be twisted to deliver nails axially arranged in the desired positions.

5. In a machine of the class described, means for axially assorting nails constructed to receive nails with their axes at an angle to the direction in which they are to be 95 driven and to arrange their corresponding faces in predetermined relative positions, and a series of guide tubes leading therefrom having passages narrower than the width of the nails whereby said nails are 100 restrained from free axial rotation.

6. In a machine of the class described, means for assorting nails axially and means for delivering the assorted nails in any desired axial relation to one another. 105

7. In a machine of the class described, the combination with an inclined grooved raceway and means for causing nails to advance along the raceway, said raceway grooves being shaped to cause the nails traveling therein to assume predetermined axial positions, of means arranged to receive the nails from the raceway grooves and automatically turn the nails entering therein to a different axial position. 110

8. In a machine of the class described, the combination with an inclined grooved raceway and means for causing nails to advance along the raceway, said raceway grooves being shaped to cause the nails traveling therein to assume predetermined axial positions, of a nail guide arranged to receive nails from the raceway and shaped to control the axial position of the nails passing therethrough. 115

9. In a machine of the class described, the combination with an inclined grooved raceway and means for causing nails to advance along the raceway, said raceway grooves being shaped to cause the nails traveling there- 130

in to assume predetermined axial positions, of nail guides presenting at the delivery end of each raceway a narrow opening into which the nails are advanced and by which 5 said nails are automatically caused to turn into a uniform axial position.

10. In a machine for assorting nails of the class described, the combination with a grooved raceway and means for causing the 10 nails to advance along the raceway, said raceway grooves being shaped to position the advancing nails with an edge uppermost, of nail guides presenting at the delivery end of each groove an opening narrower than 15 the width of the nails for controlling the axial position of the nails as they pass from the raceway.

11. In a machine for assorting nails of the class described, the combination with a 20 grooved raceway and means for causing the nails to advance along the raceway, said raceway grooves being shaped to support by one edge and one side the nails traveling therein, of nail guides presenting at the delivery end of each groove an opening of a 25 width approximately equal to the thickness of the nails whereby the axial position of the nails passing from the raceway is controlled by the side walls of the guide.

30. 12. In a machine of the class described, an inclined raceway on which the nails are dropped and down which they slide, said raceway having a series of V-shaped grooves, one side of each groove supporting one of 35 the sides of a nail while the other side of the groove sustains one of the narrow edges of the nail, whereby the nail is automatically positioned axially with one of its edges inclined upwardly that it may be delivered 40 therefrom in predetermined axial position, and means for receiving nails from said raceway constructed to control their axial position.

13. In a machine of the class described, 45 an inclined raceway on which the nails are dropped and down which they slide, said raceway having a series of V-shaped grooves, one side of each groove supporting one of the sides of a nail while the other side of the 50 groove sustains the narrow lower edge of the nail whereby said nail is positioned axially with one of its edges inclined upwardly, each groove at its delivery end having an opening or pocket of less width than the width 55 of a nail in which the nails passing down the groove are caused to enter as they leave the raceway.

14. In a machine of the class described, an inclined raceway having a series of 60 grooves to receive at their upper ends a series of nails, said raceway being constructed to turn the nails somewhat axially between the times of their contact with said raceway and their delivery therefrom, thereby to arrange

said nails with their corresponding sides in 65 predetermined relative positions, and means to conduct said arranged nails from the grooves of said raceways to the driving mechanism while maintaining the said arrangement of the nails.

70 15. In a machine of the class described, a device constructed to sustain the weight of a nail and turn the same axially in its movement over said device, and means for advancing the nails along said device.

75 16. In a machine of the class described, a raceway to receive and guide nails provided with pockets near its end narrower than the widest part of the nail, nail guiding tubes having their ends respectively opening into 80 said pockets and formed of a thickness less than the width of a nail whereby the nails are restrained from free axial rotation, said tubes being flexible and adapted to be twisted to deliver nails arranged in the desired axial positions.

85 17. In a machine of the class described, nail guiding means arranged to sustain the weight of the nails and to guide the nails in a predetermined path and constructed to 90 arrange the nails with corresponding sides in predetermined relative positions, and means for advancing the nails along said guiding means.

95 18. In a machine of the class described, automatic mechanism for assorting nails constructed to arrange the nails with their corresponding sides in predetermined relative positions irrespective of the axial positions of the nails when supplied to said 100 mechanism, including means for causing the axes of the nails to turn angularly prior to their discharge from said mechanism, and means for supplying nails to said mechanism.

105 19. In a machine of the class described, automatic mechanism for assorting nails constructed to receive nails supplied in indiscriminate relative axial positions and to insure their arrangement with corresponding sides in predetermined relative positions, including means for turning the axes of the nails angularly while being so arranged, and means for automatically supplying 110 nails to said mechanism.

115 20. In a machine of the class described, mechanism constructed to receive nails with their axes at an angle to the direction in which they are to be driven and to arrange them with their corresponding sides in predetermined relative positions regardless of the positions as to their sides in which the nails approach such mechanism, and means for automatically supplying nails to said mechanism.

120 21. In a machine of the class described, means constructed to sustain nails in an inclined position and arrange them with their

corresponding sides in predetermined relative positions, and means constructed to receive the nails after being so arranged and to control their axial position while they are being delivered to the driving mechanism.

In testimony whereof, I have signed my

name to this specification, in the presence of two subscribing witnesses.
